INVENTOR
Edward F. Donnelly
by his attorney,
Charles S. Gooding.

UNITED STATES PATENT OFFICE.

EDWARD F. DONNELLY, OF MALDEN, MASSACHUSETTS.

HOT-WATER TEMPERATURE AND PRESSURE RELIEF DEVICE.

Application filed January 4, 1924. Serial No. 684,415.

To all whom it may concern:

Be it known that I, EDWARD F. DONNELLY, a citizen of the United States, residing at Malden, in the county of Middlesex and 5 State of Massachusetts, have invented new and useful Improvements in Hot-Water Temperature and Pressure Relief Devices, of which the following is a specification.

This invention relates to a hot-water temperature and pressure relief device.

The object of the invention is to provide a simple device, which can be directly attached to the top of a hot-water boiler to automatically operate when the pressure in the boiler 15 arrives at a predetermined amount, and also when the temperature in the boiler reaches a predetermined degree, thus providing a two-fold security against the explosion of the boiler, either from an excessive pressure or 20 from an excessive temperature.

It is very desirable that a device of the character set forth should be simple and easily attached; compact and capable of being taken apart and repaired by one not particularly skilled in the art.

It is also very desirable that a device of this character should be capable of being directly attached to the top of the boiler.

The device of this invention, in order to 30 secure these ends, consists primarily of a T fitting adapted to be attached to the top of a boiler and connecting with the pipe of a service system, a valve casing with a valve therein, adapted to be attached to the T fitting and said valve being a pressure valve 35 adapted to open and close communication between the fitting and the valve casing, and a pipe projecting into the chamber of said fitting and having a fusible plug in its inner end, said pipe being connected to the atmosphere and the chamber of said valve casing 40 also being connected to the atmosphere.

In the particular embodiment of my invention hereinafter described, the pipe, with 45 the fusible plug in its inner end, which leads out of the fitting chamber, connects with a branch leading out of the valve chamber casing, which branch may be connected by a pipe to any suitable receptacle.

The device of my invention is so constructed 50 that the valve, which is spring actuated, can be set for any desired pressure, and the device by which it is set is enclosed within a cap on the valve casing, so that if desired, 55 the said cap can be sealed and prevent the

spring-adjusting member from being tampered with.

Referring to the drawings:—

Figure 1 is a front elevation of my improved hot-water temperature and pressure 60 relief device, illustrating the same as connected to a portion of a boiler broken away to save space.

Fig. 2 is a sectional elevation taken on line 2—2, Figure 1.

Fig. 3 is a detail longitudinal sectional elevation of the pipe connections, which have the fusible plug attached thereto and which connect the fitting chamber to the outlet 70 branch of the valve chamber.

Like numerals refer to like parts throughout the several views of the drawings.

In the drawings, 5 is a portion of the top of a hot-water boiler with an externally screw-threaded outlet 6. 7 is a fitting provided with a chamber 8 and having two laterally extending branches 9 and 10 internally screw threaded, an upwardly extending branch 11 also internally screw threaded, and a downwardly extending branch 12 internally screw threaded to engage the outlet 6 of the boiler.

A valve casing 13 is provided with a valve casing chamber 14, the lower end of said valve casing having screw-threaded engagement with a connecting nipple 15, which has screw-threaded engagement at its lower end with an internal screw thread of the fitting 7. The upper end of the nipple 15 is provided with a valve seat 16, upon which a valve 17 is normally seated. The valve 17 is positioned in the chamber 14 and has a stem 18 extending downwardly therefrom and slidably in a cross bar 19 in the nipple 15. Another valve stem 20 extends upwardly 95 from the valve 17 and is slidably mounted in a bearing 21 provided with a head 21' which has screw-threaded engagement with the upper end of the valve casing 13. A spring 22 encircles the stem 20 and bears at its upper end against the lower end of the bearing 21 and at its lower end against the upper face of the valve 17.

When the bearing 21 has been screwed downwardly until its head 21' engages the upper end of the casing 13, it is evident that it cannot be screwed down any further and when so screwed down, the spring 22 is compressed to an extent to enable the valve 17 to release the pressure at 130 pounds.

A cap 23 has screw-threaded engagement with the upper end of the valve casing 13 and encloses the bearing 21. The bearing 21 constitutes a means for adjusting the pressure on the spring 22. By turning it in one direction or the other the tension on the spring may be increased or diminished, due to said bearing having screw-threaded engagement with the stationary top of the valve casing 13. An outlet branch 24 extends laterally from the casing 13 and opens out of the valve casing chamber 14. Said branch 24 has an internally screw-threaded boss 25 thereon, with which an elbow 26 10 has screw-threaded engagement.

A pipe 27 is connected by a union 28 at its upper end to the elbow 26 and at its lower end is connected by a union 29 to a pipe 30 which has screw-threaded engagement at 31 20 with the fitting 7. The lower end of the pipe 30 projects into the chamber 8 and has a fusible plug 32 therein. The screw-threaded portion 31 of the pipe 30 has screw-threaded engagement with a boss 33 forming a part of 25 the fitting 7.

Pipes not shown in the drawings may have screw-threaded engagement with the branches 9 and 10 and connect with the different fixtures to which it is desired to supply hot water in the usual manner.

The general manner of use and the operation of the device hereinbefore described is as follows:—

Assuming the device to be attached to the outlet 6, as illustrated in Figures 1 and 2, and that excessive heat develops in the boiler 5, the plug 32 will melt and the heated water will pass, under pressure, through the pipes 30 and 27, elbow 26 and outlet branch 24 to 35 the outer air and to a convenient receptacle provided therefor. If the pressure in the boiler 5 becomes excessive or exceeds a certain predetermined amount, the valve 17 will move upwardly away from its seat 16 and 40 the heated water will pass upwardly through the branch 24 to said receptacle, and in each of these instances, cold water will automatically be supplied to the boiler and in the usual manner, the construction for 45 supplying this cold water not being shown thus cooling the water in the boiler and reducing the temperature and the pressure.

It will be seen that the different parts of the device of my invention may be easily assembled, for example, the pipe 30 may be disconnected from the pipe 27 by unscrewing the union nut 29 and the union nut 28, removing the pipe 27 and then removing the pipe 30 from the fitting by unscrewing the 55 screw-threaded portion 31 thereof from the boss 33. The fuse 32 is driven into the end of the pipe 30 and the parts are then reassembled.

If it is desired to increase or diminish the 60 pressure on the spring 22, the cap 23 is re-

moved and the bearing 21 is rotated clockwise or anti-clockwise respectively.

The seat 16 is a ring which may be removed from the nipple 15 and a new seat inserted in its place, the nipple 15 being unscrewed from the valve casing 13 to enable this work to be done.

In addition to the advantages hereinbefore set forth in relation to the device of this invention, it will be seen that the fusible 75 plug 32 being located in the extreme lower end of the pipe 30, and projecting into the chamber of the fitting 7, all of the water which passes out of the boiler and through the branches 9 and 10 to their respective 80 pipes must contact with the lower end of the fuse 32 and thus will at all times keep the said fuse clear of any accumulations of grease or other dirt, so that the lower end of the fuse is always bright and clean and always ready to be affected by the predetermined temperature at which it should melt.

I claim:—

1. A hot-water temperature relief device having, in combination, a pipe fitting provided with a chamber and adapted to be connected directly to the main water outlet of a boiler and having an outlet adapted to be connected to the pipe of a service system, whereby water may pass normally and uninterruptedly from said boiler through said fitting to said service system, a pipe leading from said chamber to the atmosphere and a fusible plug in the inner end of said pipe.

2. A hot-water temperature relief device 100 having, in combination, a pipe fitting provided with a chamber and adapted to be connected directly to the main water outlet of a boiler and having an outlet adapted to be connected to the pipe of a service system, whereby water may pass normally and uninterruptedly from said boiler through said fitting to said service system, a pipe projecting into said chamber and leading to the atmosphere and a fusible plug in the inner 105 end of said pipe.

3. A hot-water temperature relief device having, in combination, a pipe fitting provided with a chamber and adapted to be connected directly to the main water outlet of a boiler and having an outlet adapted to be connected to the pipe of a service system, whereby water may pass normally and uninterruptedly from said boiler through said fitting to said service system, a pipe inclined 110 at an angle to the median line of said fitting and leading from said chamber to the atmosphere and a fusible plug in the inner end of said pipe.

4. A hot-water temperature and pressure relief device having, in combination, a pipe fitting provided with a chamber and adapted to be connected directly to the main water outlet of a boiler and having an outlet adapted to be connected to the pipe of a 115

- service system, whereby water may pass normally and uninterruptedly from said boiler through said fitting to said service system, a pipe leading from said chamber to the 5 atmosphere, a fusible plug in the inner end of said pipe, a valve casing provided with a valve chamber and with an outlet orifice leading out of said valve chamber to the atmosphere, means connecting said valve 10 chamber to said fitting chamber and a valve member in said valve chamber adapted to open and close communication between said chambers and adapted to be opened by a predetermined pressure within the boiler.
- 15 5. A hot-water temperature and pressure relief device having, in combination, a pipe fitting provided with a chamber and adapted to be connected directly to the main water outlet of a boiler and having an outlet 20 adapted to be connected to the pipe of a service system, whereby water may pass normally and uninterruptedly from said boiler through said fitting to said service system, a pipe leading from said chamber to the 25 atmosphere, a fusible plug in the inner end of said pipe, a valve casing provided with a valve chamber and with an outlet orifice leading from said chamber to the atmosphere, a tubular member connecting the bottom 30 of said valve casing to the top of said fitting, whereby said valve chamber and said fitting chamber are connected together, the upper end of said tubular member constituting a valve seat and a spring-actuated valve 35 member in said valve chamber adapted to open and close communication between said chambers and adapted to be opened by a predetermined pressure within the boiler.
6. A hot-water temperature and pressure 40 relief device having, in combination, a pipe fitting provided with a chamber and adapted to be connected directly to the main outlet of a boiler and having an outlet adapted to be connected to the pipe of a service system, whereby water may pass normally and uninterruptedly from said boiler through 45 said fitting to said service system, a valve casing provided with a valve chamber, a lat-
- eral tubular branch on said valve casing opening to the atmosphere, a pipe leading 50 from said fitting chamber into said lateral tubular outlet, a tubular member connecting the bottom of said valve casing to the top of said fitting, whereby said valve chamber and said fitting chamber are connected together 55 and a valve member in said valve chamber adapted to open and close communication between said chambers and adapted to be opened by a predetermined pressure within the boiler. 60
7. A hot-water temperature and pressure relief device having, in combination, a fitting with four branches, each of said branches being internally screw threaded, one of said branches opening out of the bottom of said fitting and adapted to be fastened to the outlet of a boiler, two of said branches being lateral branches adapted to be connected to the pipes of a service system and a valve casing having a valve chamber, 70 a nipple connecting the bottom of said valve chamber to a branch on the top of said fitting, a latterly extending tubular outlet branch opening out of said valve chamber, a valve located in said valve chamber and adapted 75 to open or close communication between the valve chamber and the fitting chamber and adapted to be opened by excessive pressure within the boiler, a pipe connected to said fitting chamber and projecting at its lower 80 end into said fitting chamber, a fusible plug in the lower end of said pipe, the upper end of said pipe opening into the lateral outlet branch of said valve casing, whereby excessive pressure in said boiler will cause said 85 valve to open and allow the water in the boiler to pass outwardly through said fitting chamber and valve chamber to the atmosphere and whereby excessive temperature in said boiler will cause said fusible plug to 90 melt and the heated water under pressure to pass outwardly through said pipe and into said lateral tubular branch.

In testimony whereof I have hereunto set my hand.

EDWARD F. DONNELLY.
